UNITED STATES PATENT OFFICE.

DANIEL L. CHANDLER, OF BOSTON, MASSACHUSETTS, ASSIGNOR, BY MESNE ASSIGNMENTS, TO VEND ADS CORP., A CORPORATION OF MASSACHUSETTS.

VENDING MACHINE.

Application filed March 28, 1923, Serial No. 628,354. Renewed October 3, 1925.

To all whom it may concern:

Be it known that I, DANIEL L. CHANDLER, a citizen of the United States, residing at Boston, in the county of Suffolk and State 5 of Massachusetts, have invented new and useful Improvements in Vending Machines, of which the following is a specification.

This invention relates to vending machines.

10 The object of the invention is to provide a vending machine which will operate as follows:

15 1. When the correct coin is deposited in the machine and an article is in position ready for delivery, the machine will operate to deposit the coin in the machine, preferably in a suitable receptacle therefor, and will deliver the article to the operator of the machine.

20 2. When no coin is deposited in the machine and there is an article in position ready for delivery, the machine may be manually operated from the outside, but no article will be delivered.

25 3. When the correct coin, that is, a coin of predetermined dimensions, is deposited in the machine and there is no article positioned ready for delivery, then the coin will be returned to the operator.

30 4. When a coin or slug of dimensions other than the exact dimensions of the coin which it is intended shall be deposited in the machine is so deposited and there is an article in the machine positioned ready for delivery, the coin or slug will be returned to the operator and the article will be retained in the machine.

35 5. When a coin which is not of the correct dimensions or a slug is deposited in the machine and there is no article positioned ready for delivery, then said coin will be returned to the operator.

40 It has been found that when machines of this character are placed upon the market material other than coins, such as paper, paraffin, chewing gum, tooth picks, matches, etc., have been put into the coin slot and forced down into the machine, thus rendering the machine either inoperative or else 45 causing it to be so tampered with that the articles can be fed one by one out of the machine without any coin being introduced into the machine in payment for each of the articles so fed.

45 55 It is one of the objects of this invention

in the event of any material other than the correct coin, whether it be a slug or a coin of a different denomination not intended to be used in the machine, for instance, a ten cent piece where the machine is designed to be operated by a penny, to positively eject said material or coin from the coin slot of the operating mechanism so that the mechanism shall not be rendered inoperative and so that the machine cannot be operated to deliver the articles without proper recompense therefor.

The machine of this invention in some respects resembles the machine for which applicant has made application for Letters 70 Patent entitled "Coin operated vending machine", filed January 19, 1923, Serial No. 613,754, but differs materially from the invention of said application in many respects.

75 One of the novel features of this invention is embodied in a rotary member which performs the function of feeding the coin out of the coin slot and depositing it in the casing of the machine, and also performs the function of feeding a coin of the wrong denomination or foreign matter which may have been introduced through the coin slot, down a chute which leads out of the machine. This rotary member also performs the function of operating the mechanism for feeding the article from a magazine to a chute which leads out of the machine. Said rotary member performs the further function of closing a portion of the coin slot, while the coin and the article to be vended are being fed so that the foreign material or other coins cannot be introduced into said slot.

80 85 Another novel feature of this invention resides in the mechanism for detecting a slug, a coin of different denomination than that which the machine is intended to handle and such articles as a washer, which although they may be of the same diameter and thickness as the coin intended to be handled by the machine, still this detector will operate 90 in such a manner as to cause such an article to be ejected from the machine.

95 100 The invention consists in the improved mechanism whereby the objects hereinbefore set forth are accomplished and particularly 105 in the combination of elements set forth in the following claims.

110 Referring to the drawings:

Figure 1 is a front elevation of a vending machine embodying my invention.

Fig. 2 is an underneath plan of the same.

Fig. 3 is a sectional elevation taken on the line 3—3 of Fig. 2, illustrating the rotary coin feeding member and other mechanism 5 actuated thereby.

Fig. 4 is a sectional elevation taken on the line 4—4 of Fig. 3 illustrating the coin and article chutes and a portion of the mechanism by which the coin chute cover is operated. 10

Fig. 5 is a detail plan broken away and showing the coin and article chutes.

Fig. 6 is a plan view of the coin detecting mechanism broken away and partly shown 15 in section.

Fig. 7 is a sectional plan similar to Fig. 6 illustrating the parts in different positions.

Fig. 8 is a sectional elevation taken on the line 8—8 of Fig. 1 illustrating the coin 20 slot mechanism and a portion of the rotary coin feeding member.

Fig. 9 is a sectional elevation similar to Fig. 8 showing the parts in different positions.

Fig. 10 is a detail sectional elevation 25 taken on the line 10—10 of Fig. 2 illustrating a pawl and ratchet mechanism used in connection with the rotary feed member shaft.

Fig. 11 is a sectional elevation through 30 one of the housings taken on the line 11—11 of Fig. 3.

Fig. 12 is a perspective view of two housings located on the top of the cover showing 35 the slot through which the coin is introduced into the machine.

Fig. 13 is an underneath plan of the secondary slide.

Fig. 14 is an underneath plan of the primary slide.

Fig. 15 is a perspective view of one of the housings broken away and showing the stop plate and a coin with a wire attached thereto illustrating the position assumed by 45 the coin when it is attempted to withdraw the same from the casing.

Fig. 16 is an elevation of a coin with the pair of detector fingers shown in section relatively thereto.

Fig. 17 is an elevation of a washer with the pair of detector fingers shown in section in connection therewith.

Like numerals refer to like parts throughout the several views of the drawings.

In the drawings, 15 is the casing of the machine, 16 is the magazine for holding the articles to be vended, 17 is a receptacle for the coins which are delivered outside the machine and 18 is the top, or cover, of the casing upon which is mounted the magazine and on the under side of which is mounted substantially all of the working mechanism of the machine.

There are embodied in the machine a

primary slide 19 and a secondary slide 20. The primary slide carries with it the larger part of the working mechanism of the machine and this primary slide is always operated to move toward and away from the front of the machine by a handle 22 fast to a shaft 23 rotatably mounted in bearings 24 which project downwardly from the under side of the top 18. A spring 25 is fastened at one end thereof to an arm 26 fast to the shaft 23 and at the other end thereof is fastened to a pin 27 projecting downwardly from the cover 18. This spring operates to rotate the shaft 23 in the opposite direction from that in which it is rotated by the handle 22. The shaft 23 is provided with a pawl and ratchet mechanism, see Figs. 2 and 10, which insures the forward movement of the primary slide being continued to its end after it has once been started, and also insures the rearward movement of the slide being carried to its end when it has once been started. This pawl and ratchet mechanism consists of a segmental ratchet 26 fast to the shaft 23 and adapted to be engaged by a pawl 27 pivotally mounted on a stud 28 which is fast to an arm 29 on one of the bearing brackets 24 depending from the cover 18 of the machine. A spring 30 is connected at one end 35 to the pawl 27 and at the other end to a pin 31 fast to the cover of the machine.

When the operator starts the machine by pulling the handle 22 toward the front thereof, the teeth of the segmental ratchet 26 will rotate in the direction of the arrow *a*, Fig. 10, and will be engaged by the swinging pawl 27 which will prevent the ratchet 26 from being moved in the opposite direction until the teeth of the ratchet pass out of engagement with the free end of the pawl 27, then when the direction of rotation of the ratchet 26 is reversed by the action which will occur when the handle is released by the operator on account of the spring 25, the pawl 27 will be tipped in the opposite direction and will engage the teeth of the segment 26 to prevent the ratchet from being rotated in the direction of the arrow *a* until the teeth of the segment again 110 pass out of engagement with the free end of the pawl 27.

The inner end of the shaft 23 has a rotary member 32 fast thereto which when the parts are in the normal positions occupies the position illustrated in Fig. 3 and in Fig. 8. The member 32 is the rotary coin feeding member which performs the functions of feeding the coin, clearing the coin slot and feeding the mechanism whereby the article is carried or fed and consists preferably of a thin disc-like member having a semi-circular recess 33 in its periphery to receive a coin 34. The member 32 has a cam-shaped periphery 35 and projects into 115

a slot 36 provided in the primary slide 19 which has a pair of oppositely disposed ears 37 between which the rotary member 32 is positioned to rock. A cam slot 38 is provided in the rotary member 32 and through this cam slot a pin 39 projects which is fastened at its opposite ends to the ears 37. The primary slide is slidably mounted in ways 40 on the under side of the cover 18 so that when the shaft 23 is rocked by the handle 22 and by the spring 25 alternately in opposite directions, the primary slide 19 will be moved forwardly or rearwardly respectively, sliding in said ways 40.

When in its normal position, the rear end of the slide 19 abuts against a stop plate 41 fast to the under side of the cover as in Figs. 2 and 3 and is held thereagainst by a spring 19'.

The present embodiment of my invention as illustrated is particularly adapted to contain and feed spherical articles such as balls of chewing gum and the magazine 16 is provided with a base 42 which forms a part of the cover 18 and in this base is a recessed portion 43 with inclined ways 44 operating to guide the balls of gum into a tubular receptacle 45 projecting downwardly from the under side of the primary slide 19 and forming a part thereof. Vertical pins 46 are fastened to the primary slide 19 and project upwardly into the magazine 16 and into the recessed portion 43 of the base of said magazine so that as the primary slide 19 is moved forwardly and backwardly, the pins 46 will agitate the articles in the magazine 16 and facilitate the feeding of the same into the receptacle 45.

A housing 47 is fast to the upper face of the cover 18 and has a vertical slot 48 therein in which is positioned a swinging arm 49 to the lower end of which is affixed a curved segmental plate 50. The arm 49 is pivoted at 51 to the housing 47 and the segmental plate 50 has a gear tooth 52 projecting downwardly therefrom into a corresponding notch 53 provided in the upper surface of the primary slide 19, so that when a reciprocatory motion is imparted to the slide 19, as hereinbefore described, a rocking motion will be imparted to the arm 49 and segmental plate 50. The segmental plate 50 has pivotally mounted thereon a rocker pin 54 mounted to rock in the segmental plate 50 and projecting beyond the opposite faces of said plate. To one end of said rocker pin 54 is fastened a cam plate 55 and to the other end of said rocker pin is fastened a detent 56 which is located in a vertical plane in alignment with the coin slot 36 in the primary slide 19.

The slot 48 is an upward extension of the coin slot 36 and the segmental plate has a laterally extending flange 57 on its upper edge and projecting over the detent 56.

Before the machine is operated to deliver the article and the coin, the parts are in the respective positions illustrated in Fig. 8, and it is evident that at this time a coin 34 may be slipped into the slot 48 and will fall downwardly into the semi-circular recess 33 in the rotary member 32, as illustrated in Fig. 8, there being space between the rear edge of the flange 57 and the front edge of the arm 49 to allow it so to do.

A spring 58 is mounted on the segmental plate 50 and the free end thereof bears against a pin 59 and thus tends to rock the cam plate 55 upon its pivot to hold the same in engagement with a cam 60.

When the arm 49 and segmental plate 50 are moved by the reciprocatory motion of the primary slide 19 acting through the tooth 52 from the position illustrated in Fig. 8 to the position illustrated in Fig. 9, the cam plate 55 and rocker pin 54 will be moved by the spring 58 to cause the detent 56 to assume the position illustrated in Fig. 9, thus narrowing the coin slot 48 sufficiently to prevent a coin 34 from being pulled upwardly out of the machine.

Another means for preventing the coin from being withdrawn from the machine is provided by a horizontal stop plate 61 which has an inclined edge 62 thereon, and if the coin 34 should be pulled upwardly out of the rotary member 32 by any means, such as a string, it will strike this plate and be diverted to a position transversely of the inclined edge 62 as illustrated in Fig. 15 so that anyone trying to tamper with the machine by withdrawing the coin by means of a string or wire attached thereto would be prevented from so doing by this plate 61.

Another housing 63 is fastened to the cover 18 in front of the housing 47 and is provided with a coin slot 64. When the arm 49 is rocked forwardly, the segmental plate 50 will move forwardly in the interior of the housing 63 as in Fig. 9.

The secondary slide 20 is slidably mounted in ways 65 and 66 on the under side of the cover 18 and normally this slide remains stationary with its rear end engaging a stop bracket 67, Fig. 2, that is, the secondary slide remains stationary if the coin which has been inserted in the machine is the right coin and the article is ready for delivery, but if the coin is not the right coin, or if the article is not ready for delivery, or if there is neither the right coin nor the right article ready for delivery, then the secondary slide 20 will be moved to prevent an article from being delivered or to return the coin to the one who is operating the machine, and these results are attained by the mechanism which will now be described.

First as to the mechanism for returning a slug or coin which is not of the right dimensions; a lever 68 is pivoted at 69 to the pri-

mary slide 19, and this lever has a pin 70 fast thereto and projecting upwardly therefrom to engage the cam shaped edge 71 of a cam plate 72 which is fastened to the under 5 side of the cover 18. A spring 73 tends to hold the pin 70 against the cam shaped edge 71. The lever 68 is provided with an arm 74 which has a pin 75 projecting upwardly therefrom and extending through a slot 76 10 provided in a plate 77 constituting a compensating member which is pivotally connected by pins 78 and 79 to feeler fingers 80 and 81. The feeler fingers 80 and 81 are slidably mounted in the primary slide 19 15 and are adapted to engage a coin or other article 34 when the same is in the recess 33 in the rotary member 32, and the fingers 80 and 81 will both of them bear against the coin due to their being forced thereagainst 20 by the lever 68 and by the plate 77. If the fingers 80 and 81 are in the correct position which they would assume if the coin is the correct coin, and if at the same time there 25 is an article, as in the present case, a ball of gum 82, Fig. 3, positioned in the tube 45, then the primary slide will move forwardly when caused to do so by the rotary movement of the member 32 in the direction of the arrow *b*, Fig. 3, and the coin will be 30 dropped out of the recess 33 and upon the top of an inclined cover 83, Fig. 4, down which it will slide and onto an inclined plate 84 from which it will drop onto the bottom 35 of the casing and the gum delivered.

35 If the coin or slug which is positioned in the recess 33 is thinner than a penny, then the feeler fingers 80 and 81 will allow the lever 68 to move toward the right, Fig. 6, when the primary slide 19 is moved forwardly and when the pin 70 arrives opposite the notch 86 in the edge 71 of the cam plate 72, whereupon a stud 87 which projects upwardly from the lever 68 will engage a projection 88 on the secondary slide 20, and upon further movement forward, the slide 20 will move with the slide 19 and a pin 89 which projects downwardly from the slide 20 and through an inclined slot 90 in a bracket 91 fast to the hinged cover 83 will 40 cause said hinged cover to tip from the position shown in full lines to that shown in dotted lines, Fig. 4, and then when the penny is dropped out of the rotary member 32, it will pass downwardly and onto an inclined V-shaped chute 92 which will conduct the penny out of the casing to the receptacle 17 where it can be obtained by the 45 user of the machine.

60 The cover 83 is hinged at 93 to an auxiliary casing 94 fast to the front of the casing 15, and a spring 95 which is fast at one end to the bracket 91 and at the other end to a bracket 96 on the auxiliary casing 94 will normally hold the cover 83 in the position 65 shown in full lines in Fig. 4, and abutting

against a stop 97 on the auxiliary casing 94.

If the coin or slug which is in the recess 33 is thicker than a penny, then the stud 87 will engage a projection 98 on the free end of a lever 99 which is pivoted at 100 to the secondary slide 20. A spring 101 is fastened at one end thereof to a pin 102 on the secondary slide 20 and at the other end thereof to a pin 103 on the lever 99. An ear 104 projects downwardly from the lever 99 and normally the spring 101 acts to hold the ear 104 against the edge of the secondary slide 20. When the projection 87 engages the projection 98 the slide 20 will be moved together with the primary slide 19 and the coin which is thicker than a penny will be dropped in the same manner as hereinbefore described in relation to a coin which is thinner than a penny, and will pass downwardly through the auxiliary casing 94, 85 along the chute 92 and onto the receptacle 17.

By reference to Fig. 6, it will be seen that the feeler finger 80 is concentric with the recess 33 in the rotary member 32 and the feeler finger 81 projects a very slight distance within the periphery of the recess 33. The object of this relative positioning of the fingers to the recess 33 is as follows:—Assuming that a washer 105 such as is illustrated in Fig. 17 is of the same thickness as a penny, then the finger 80 will project into the hole in the washer and the lever 68 will then be moved into the notch 86 when the primary slide is moved forwardly so that the projection 87 will engage the projection 88 on the secondary slide 20 with the result hereinbefore set forth in relation to a thin coin; that is, the washer will be ejected from the machine and the article will not be delivered.

If a slug of a diameter slightly smaller than a penny be introduced into the recess 33, even though it be the same thickness as a penny, it will be ejected from the machine 110 for the reason that the feeler finger 81 will pass by the edge of such a slug with the same results as hereinbefore described in relation to the thin coin and the washer. It will be noted that the outermost edge 106 of the projection 98 is inclined and the rear edge of the projection 87 is also inclined so that if the secondary slide 20 remains stationary while the primary slide is moved forwardly and backwardly, which is the case when the article is of the right size and the coin is of the correct size, upon the return movement of the primary slide, the lever 99 will be caused to swing toward the left, Fig. 6, and allow the projection 87 to 115 pass by the projection 106.

It will, therefore, be understood that if the coin is of the right diameter and there is an article in the tube 45 ready to be delivered, the projection 87 on the lever 68 120

will pass between the projections 88 and 98 and the slide 20 will remain stationary, when the coin will be deposited by the rotation of the member 32 in the casing as hereinbefore described.

The stud 87, projection 88 and projection 98 constitute contacts and will be referred to as such in the claims. From the foregoing description, it will be understood that the lever 68, the plate 77 and the feeler fingers 80 and 81 constitute, as a whole, a compensating mechanism, whereby two different parts of the coin must be of the right thickness, or otherwise the lever 68 will be operated to move the slide 20 and cause the coin to be ejected from the machine, and because of the pivoted connection of the fingers 80 and 81 to the plate 77 and of the pivoted connection of the plate 77 to the lever 68, the feeler fingers 80 and 81 may move into different positions toward and away from the coin, or the recess 33 in which it is located without cramping the compensating mechanism in any way.

It will be understood that both the coin and the article must be present in the machine in order that an article may be delivered. It has been hereinbefore described how the coin will be ejected from the machine if it is not of the proper size and it will now be described how the coin will be ejected from the machine if there is no article to be delivered, thus making sure that the user of the machine will receive his money back if he does not obtain an article from the machine in exchange therefor, and this is accomplished by means of a detector finger 107 which is pivoted at 108 to an arm 109 fast to the primary slide 19. This detector finger has an arm 110 thereon which projects through a slot 111 in the tube 45 and a spring 112 acts to move the arm 110 toward and into the tube 45. The finger 107 has a projection 113 extending upwardly therefrom and adapted to engage the edge 71 of the cam plate 72 which has a notch 114 therein so that as the primary slide is moved forwardly, the pin 113 will descend into the notch 114 if there is no article in the tube 45 to prevent its so doing, and in that case, an ear 115 constituting a contact point will engage a stud 116 also constituting a contact point on the secondary slide 20 and thus the secondary slide will be moved forward and the coin will be ejected as hereinbefore described. If, however, there is an article in the tube 45, then the detector finger 107 will be held out and the contact 115 will not engage the contact 116, and so far as this mechanism is concerned, the slide 20 will not be moved forward. A bracket 117 is fastened to the secondary slide 20 and has a horizontal arm 118 thereon, Fig. 3, which projects through the tube 45 and the article 82 will rest upon this arm

118 and be prevented from dropping out of the tube 45 when the secondary slide 20 moves together with the primary slide 19, in which case there will be no article delivered from the machine. If, however, the secondary slide remains stationary, which it always will when the article is ready to be delivered and the coin is of the right size, in that case the primary slide will move forwardly, carrying the article 82 with it and at the end of the forward movement of the primary slide, the article will be pushed off of the arm 118 and dropped downwardly in the tube 45 and onto a stationary shelf 119, then upon a return movement of the primary slide, the article will be pushed off of the stationary shelf 119 by the tube 45 and will fall into a tube 120 which, being inclined downwardly, will cause the article to roll down to the outer end thereof which projects out of the casing, and at the outer end of said tube the ball of gum will engage a cover 121 which is pivoted at 122 to the frame of the machine, and is kept normally closed by gravity. The user of the machine can then obtain the gum by pressing upon the upper end of an arm 124 on said cover so as to open the end of the tubular chute 120.

The general operation of the mechanism hereinbefore specifically and to some extent in general described is as follows:—The user of the machine places a coin of the proper dimensions, that is, a penny for a penny machine, a nickel for a nickel machine or a dime for a dime machine in the coin slot 48, and it passes downwardly through said slot between the arm 49 and the rear edge of the flange 57 and the rear edge of the detent 56 and drops into the recess 33 in the rotary member 32 as illustrated in Fig. 8. The operator then rotates the shaft 23 and the rotary member 32 by means of the handle 22 in a counter-clockwise direction, that is, in the direction of the arrow b Fig. 3 by pulling the handle toward the front of the machine.

Assuming now that there is an article 82 in the tube 45 and that the coin is of the correct dimensions, the primary slide 19 will be moved forwardly by the pin 39 in the cam slot 38 and the lever 68 and the detector finger 107 will move with it. Since there is an article in the tube 45, the contact 115 on the lever 107 will clear the contact 116 on the slide 20 and since the coin is of the right dimensions, the contact 87 on the lever 68 will pass between the contacts 88 and 98 and therefore the slide 20 will remain stationary. The rotary member will be rotated until the coin 34 is dumped onto the inclined cover 83 down which it will slide onto the inclined plate 84 and from thence it will fall onto the bottom 85 of the casing, at the same time

the article 82 will be pushed along the arm 118 and will drop on the shelf 119 and upon the return movement of the slide 20, the article will be pushed off of the shelf 119, and dropping into the tube 120 will roll down said tube against the cover 121 where it may be obtained by the user of the machine as hereinbefore described.

Assuming that the combination of circumstances should occur as set forth in paragraph 2 where there is no coin deposited in the machine but there is an article 82 in the tube 45 positioned ready for delivery, in this case when a machine 5 is operated by the handle 22 as hereinbefore described, the compensating lever 68 will be moved as hereinbefore described to cause the contact 87 to engage the contact 88 and the primary slide and secondary slide will 10 then move together, the coin will be ejected from the machine, as hereinbefore described, and the article will remain in the machine resting on the arm 118 and when the handle is released, the parts will return 15 to the relative positions illustrated in 20 Fig. 3.

When the combination of circumstances set forth in paragraph 3 occurs wherein a correct coin is deposited but there is no 25 package, then the coin detector finger is positioned correctly so that the coin will be delivered, that is, the contact 87 will pass between the contacts 88 and 98 and so far as this portion of the mechanism is concerned, the slide 20 will remain stationary, but the article detector finger will be moved 30 so that the contact 115 will engage the contact 116 and this will move the slide 20 as hereinbefore described so that an article 35 will not be delivered and the coin will. 40

If the combination of circumstances set forth in paragraph four occurs wherein a coin or slug of dimensions other than the exact dimensions which is intended to be deposited in the machine is placed in the machine and there is an article positioned in the machine ready for delivery, the lever 45 50 68 will be operated as hereinbefore described to cause the slide 20 to move with the slide 19 and the coin or other slug will be ejected from the machine and the article will be retained in the machine.

When the combination of circumstances set forth in paragraph 5 occurs and there is 55 a slug which is thinner than a penny positioned in the recess 33, or if there is a slug thicker than a penny, or a washer, or a coin of smaller diameter than a penny, then the lever 68 will be moved as hereinbefore 60 described so that the contact 87 will engage either the contact 88 or the contact 98 and the slides 19 and 20 will then move together and the coin, slug, or whatever it may be, will be ejected from the machine.

65 It has been found that in order to obtain

articles from the machine without paying for them certain persons have attached a string or wire to the coin and dropped it into the machine, and after having moved the parts to just the right position 70 to obtain an article, have pulled the coin back out of the machine. In the present machine, this is prevented by the detent 56 which moves into the position illustrated in Fig. 9 and thus makes the coin slot so 75 narrow that the coin cannot be drawn back out of the machine and also such an act is prevented by reason of the stop plate 61 with its inclined edge 62 which will operate to turn the coin across the coin slot 80 if anyone tries to draw the coin upwardly and outwardly after it has been ejected from the rotary member 32, as illustrated in Fig. 15.

I claim:

1. A machine for delivering an article in exchange for a coin of predetermined dimensions having, in combination, a casing, a coin holder rotatably mounted on said casing and having a recess in its periphery to hold said coin, said casing having a coin slot in alignment with said recess, means for testing a coin in said recess, means to rotate said coin holder and mechanism operated thereby to cause said coin to be ejected from said holder and deposited in said casing. 90

2. A machine for delivering an article in exchange for a coin of predetermined dimensions having, in combination, a casing, a coin holder rotatably mounted on said casing and having a recess in its periphery to hold said coin, said casing having a coin slot in alignment with said recess, means to rotate said coin holder and mechanism including an article-receiving slide operated thereby to cause a coin other than one of predetermined dimensions to be ejected from said coin holder and from said casing. 100

3. A machine for delivering an article in exchange for a coin of predetermined dimensions having, in combination, a casing, a coin holder rotatably mounted on said casing and having a recess in its periphery to hold said coin, said casing having a coin slot in alignment with said recess, means for testing a coin in said recess, means to rotate said coin holder and mechanism operated thereby to cause an object other than a coin of predetermined dimensions to be ejected from said coin holder and from said casing. 110

4. A machine for delivering an article in exchange for a coin of predetermined dimensions having, in combination, a casing, a slide constituting a carrier for an article, a coin holder rotatably mounted on said casing and having a recess in its periphery to hold said coin and mounted in a slot provided in said slide in alignment with a slot provided in said casing, means to simultaneously rotate said coin holder and re- 120 125 130

ciprocate said slide and mechanism operated thereby to cause said coin to be retained in said casing and to cause said article to be delivered therefrom.

5 5. A machine for delivering an article in exchange for a coin of predetermined dimensions having, in combination, a casing, a slide constituting a carrier for an article, a coin holder rotatably mounted on said casing and having a recess in its periphery to hold said coin and mounted in a slot provided in said slide in alignment with a slot provided in said casing, means to simultaneously rotate said coin holder and reciprocate said slide and mechanism operated thereby to cause a coin other than one of predetermined dimensions to be ejected from said coin holder and from said casing and to prevent said article from being delivered

20 therefrom.

6. A machine for delivering an article in exchange for a coin of predetermined dimensions having, in combination, a casing, a slide constituting a carrier for an article, a coin holder rotatably mounted on said casing and having a recess in its periphery to hold said coin and mounted in a slot provided in said slide in alignment with a slot provided in said casing, means to simultaneously rotate said coin holder and reciprocate said slide and mechanism operated thereby to cause an object other than a coin of predetermined dimensions to be ejected from said casing and to prevent said article from being delivered therefrom.

7. A machine for delivering an article in exchange for a coin of predetermined dimensions having, in combination, a casing, a slide constituting a carrier for an article, a rotary coin holder in said casing, with a recess in its periphery to hold said coin and mounted in a slot provided in said slide in alignment with a slot provided in said casing, means to simultaneously rotate said coin holder and reciprocate said slide in a direction transversely of the axis of said coin holder and mechanism operated thereby to cause said coin to be retained in said casing and to cause said article to be delivered

60 therefrom.

8. A machine for delivering an article in exchange for a coin of predetermined dimensions having, in combination, a casing, a slide constituting a carrier for an article, a rotary coin holder in said casing with a recess in its periphery to hold said coin and mounted in a slot provided in said slide in alignment with a slot provided in said casing, the periphery of said coin holder being cam-shaped, means to simultaneously rotate said coin holder and reciprocate said slide in a direction transversely of the axis of said coin holder, and mechanism operated thereby to cause said coin to be retained in said

casing and to cause said article to be delivered therefrom.

9. A machine for delivering an article in exchange for a coin of predetermined dimensions having, in combination, a casing, a slide constituting a carrier for an article, a rotary coin holder in said casing with a recess in its periphery to hold said coin and mounted in a slot provided in said slide in alignment with a slot provided in said casing, means to rotate said coin holder, a cam incorporated in said holder engaging said slide to impart a reciprocatory motion thereto transversely of the axis of the coin holder and mechanism operated by said slide to cause said coin to be retained in said casing and to cause said article to be delivered

10. A machine for delivering an article in exchange for a coin of predetermined dimensions having, in combination, a casing, a slide constituting a carrier for an article, a rotary coin holder in said casing with a recess in its periphery to hold said coin and mounted in a slot provided in said slide in alignment with a slot provided in said casing, means to rotate said coin holder, a cam incorporated in said holder engaging said slide to impart a reciprocatory motion thereto transversely of the axis of the coin holder and mechanism operated by said slide to cause a coin other than one of said predetermined dimensions to be ejected from said coin holder and from said casing and to prevent said article from being delivered

therefrom.

11. A machine for delivering an article in exchange for a coin of predetermined dimensions having, in combination, a casing, a slide constituting a carrier for an article, a rotary coin holder in said casing with a recess in its periphery to hold said coin and mounted in a slot provided in said slide in alignment with a slot provided in said casing, means to rotate said coin holder, a cam incorporated in said holder engaging said slide to impart a reciprocatory motion thereto transversely of the axis of the coin holder and mechanism operated by said slide to cause an object other than a coin of predetermined dimensions to be ejected from said casing and to prevent said articles from being delivered therefrom.

12. A machine for delivering an article in exchange for a coin of predetermined dimensions having, in combination, a casing provided with a coin slot, a coin holder rotatably mounted on said casing and having a recess in its periphery to hold said coin, a primary slide slidable on said casing and constituting a holder for an article, a secondary slide on said casing and means on said secondary slide to prevent an article being delivered from said primary slide

when said slides are connected to move together and means governed by said articles to connect said slides together.

13. A machine for delivering an article in exchange for a coin of predetermined dimensions deposited therein having in combination, a casing, a coin holder rotatably mounted in said casing and having a recess therein to hold said coin, said casing having a coin slot in alignment with said recess, a primary slide constituting a carrier for an article, slideable in said casing, means to simultaneously rotate said coin holder and reciprocate said slide, a pair of feeler fingers on said primary slide normally in alignment with said recess, a lever pivoted to said slide and connected to said feeler fingers, means to rock said lever, a contact forming a part of said lever, a secondary slide slideable on said casing, a contact forming a part of said secondary slide and adapted, when an object other than a coin of predetermined dimensions is located in said coin holder recess, to be engaged by said lever contact, and means to guide said coin when ejected from said coin holder to deposit the same in said casing, said means being adapted to be positioned by the movement of said secondary slide to guide an object other than a coin of predetermined dimensions out of said casing.
14. In a machine for delivering an article in exchange for a coin of predetermined dimensions deposited therein having, in combination, a casing, a coin holder rotatably mounted in said casing and having a recess therein to hold said coin, said casing having a coin slot in alignment with said recess, a primary slide constituting a carrier for an article, slideable in said casing, means to simultaneously rotate said coin holder and reciprocate said slide, a pair of feeler fingers on said primary slide normally in alignment with said recess, a lever pivoted to said slide, a compensating member connecting said feeler fingers to said lever, means to rock said lever, a contact forming a part of said lever, a secondary slide slideable on said casing, a contact forming a part of said secondary slide and adapted when an object other than a coin of predetermined dimensions is located in said coin holder recess to be engaged by said lever contact and means to guide said coin when ejected from said coin holder to deposit the same in said casing, said means being adapted to be positioned by the movement of said secondary slide to guide an object other than a coin of predetermined dimensions out of said casing.
15. A machine for delivering an article in exchange for a coin of predetermined dimensions deposited therein having, in combination, a casing, a coin holder rotatably mounted in said casing and having a recess

therein to hold said coin, said casing having a coin slot in alignment with said recess, a primary slide constituting a carrier for an article, slideable in said casing, means to simultaneously rotate said coin holder and reciprocate said slide, a pair of feeler fingers on said primary slide in alignment with said recess, a lever pivoted to said slide and connected to said feeler fingers, a stationary cam plate and a spring acting to move said lever into contact therewith, a contact forming a part of said lever, a secondary slide slideable on said casing, a contact forming a part of said secondary slide and adapted, when an object other than a coin of predetermined dimensions is located in said coin holder recess, to be engaged by said lever contact and means to guide said coin when ejected from said coin holder to deposit the same in said casing, said means being adapted to be positioned by the movement of said secondary slide to guide an object other than a coin of predetermined dimensions out of said casing.

16. A machine for delivering an article in exchange for a coin of predetermined dimensions deposited therein having, in combination, a primary slide constituting an article receptacle and a secondary slide in said casing, a coin holder rotatably mounted on said casing and provided with a recess adapted to receive a coin, a detector member on said primary slide adapted to engage a coin or other material in said recess, another detector member on said primary slide adapted to engage an article on said slide, either of said fingers being adapted to engage said secondary slide and move it with said primary slide and guiding means operable by the movement of said secondary slide with said primary slide to cause an object other than a coin of predetermined dimensions to be ejected from said casing.

17. A machine for delivering an article in exchange for a coin of predetermined dimensions deposited therein having, in combination, a primary slide constituting an article receptacle and a secondary slide in said casing, a coin holder rotatably mounted on said casing and provided with a recess adapted to receive a coin, a detector member on said primary slide adapted to engage a coin or other material in said recess, another detector member on said primary slide adapted to engage an article on said slide, either of said detector members being adapted to engage said secondary slide and move it with said primary slide, and means rendered operable by the movement of said secondary slide with said primary slide to prevent said article from being ejected from said primary slide.

18. A machine for delivering an article in exchange for a coin of predetermined dimensions deposited therein having, in com-

bination, a primary slide constituting an article receptacle and a secondary slide in said casing, a coin holder rotatably mounted on said casing and provided with a recess 5 adapted to receive a coin, a detector member on said primary slide adapted to engage a coin or other material in said recess, another detector member on said primary slide adapted to engage an 10 article on said slide, either of said detector members being adapted to engage said secondary slide and move it with said primary slide, means rendered operable by the movement of said secondary slide with 15 said primary slide to guide an object which may be located in said coin holder recess other than a coin of predetermined dimensions out of said casing and means rendered operable by the movement of said secondary 20 slide with the primary slide to prevent said article from being ejected from said slide.

19. A machine for delivering an article in exchange for a coin of predetermined dimensions deposited therein having, in combination, a primary slide constituting an article receptacle and a secondary slide in said casing, a coin holder rotatably mounted on said casing and provided with a recess 25 adapted to receive a coin, a detector member 30 on said primary slide adapted to engage a coin or other material in said recess, another detector member on said primary slide adapted to engage an article on said slide, either of said detector members being adapted to engage said secondary slide and move it with said primary slide and means rendered operable by the movement of said secondary slide with said primary slide to eject 35 an object other than a coin of predetermined 40 dimensions from said casing, said coin detector member being rendered inoperable by a coin of predetermined dimensions positioned in said recess to connect said secondary slide to said primary slide.

45 20. A machine for delivering an article in exchange for a coin of predetermined dimensions deposited therein having, in combination, a primary slide constituting an article receptacle and a secondary slide in 50 said casing, a coin holder rotatably mounted on said casing and provided with a recess adapted to receive a coin, a detector member on said primary slide adapted to engage a coin or other material in said recess, another 55 detector member on said primary slide adapted to engage an article on said slide, either of said detector members being adapted to engage said secondary slide and move it with said primary slide and means oper- 60 ated by the movement of said secondary slide with said primary slide to prevent said article from being ejected from said primary slide, said article detector member being rendered inoperable by an article on said

primary slide to connect said secondary to 65 said primary slide.

21. A machine for delivering an article in exchange for a coin of predetermined dimensions deposited therein having, in combination, a casing, a coin holder rotatably mounted in said casing and having a recess therein to hold said coin, said casing having a coin slot in alignment with said recess, a primary slide constituting a carrier for an article slidable in said casing, means to simultaneously rotate said coin holder and reciprocate said slide, a pair of feeler fingers on said primary slide in alignment with said recess, a lever pivoted to said slide and connected to said feeler fingers, means to rock said lever, a contact forming a part of said lever, a secondary slide slidable on said casing, a contact member pivotally mounted on said secondary slide and adapted when an object other than a coin of predetermined dimensions is contained in said coin holder recess to be engaged by said lever contact and means to guide said coin when ejected from said coin holder to deposit the same in said casing, said guiding means being adapted to be positioned by the movement of said secondary slide to guide an object other than a coin of predetermined dimensions out of said casing.

22. A machine for delivering an article in exchange for a coin of predetermined dimensions having, in combination, a casing, a slide constituting a carrier for an article, a coin holder rotatably mounted on said casing and having a cam-shaped periphery and a recess in its periphery to hold said coin and mounted in a slot provided in said slide in alignment with a slot provided in said casing whereby material located in said slots may be ejected therefrom.

23. A machine for delivering an article in exchange for a coin of predetermined dimensions having, in combination, a casing, a slide constituting a carrier for an article, a coin holder rotatably mounted on said casing and having a recess in its periphery to hold said coin and mounted in a slot provided in said slide in alignment with a coin slot provided in said casing, an arm pivotally mounted in said coin slot and adapted to be rocked in said slot by engagement with said slide, a detent positioned in said slot and pivotally mounted upon said arm, and a stationary cam adapted to be engaged by said detent whereby said detent may be alternately rocked in opposite directions to open said slot and permit a coin to be inserted in said casing and to obstruct said slot to prevent said coin from being withdrawn from said casing.

In testimony whereof I have hereunto set my hand.

DANIEL L. CHANDLER,
